GAUGE

William A. Czapar, Chicago, and Marshall Miles, Wilmette, Ill., assignors to Stewart-Warner Corporation, Chicago, Ill., a corporation of Virginia

Filed May 15, 1963, Ser. No. 74,896

Term of patent 14 years

(Cl. D52—6)

FIG. 1.

FIG. 2.

FIG. 1 is a perspective view taken from the front and to one side of a gauge embodying our new design, and

FIG. 2 is a fragmentary side view partially in section of the gauge shown in FIG. 1, the sectional portion being taken substantially along the line 2—2 of FIG. 1.

The rear of the gauge is substantially plain in appearance.

We claim:

The ornamental design for a gauge, substantially as shown and described.
